Primary Examiner — Keli L Hill*Assistant Examiner* — Harold E Blackwell, II(74) *Attorney, Agent, or Firm* — Xuan Zhang(57) **CLAIM**

The ornamental design for a plant grow light, as shown and described.

DESCRIPTION

FIG. 1 is a front view of a plant grow light showing my new design;

FIG. 2 is a left view thereof;

FIG. 3 is a right view thereof;

FIG. 4 is a rear view thereof;

FIG. 5 is a top view thereof;

FIG. 6 is a bottom view thereof;

FIG. 7 is a top perspective view thereof; and,

FIG. 8 is a top perspective view thereof, illustrating a retractable shaft of the plant grow light being retracted to selectively shorten a length thereof so as to selectively adjust a position of a light ring of the plant grow light.

The broken lines in the drawings are included for the purpose of illustrating environmental structure and form no part of the claimed design.
